BEARING AND FRICTION LOCK

Robinson H. Harsh, Washington, D. C.

Application December 16, 1930, Serial No. 502,825
Renewed July 2, 1934

4 Claims. (Cl. 292—73)

This invention relates to furniture and more particularly to a novel drawer guide and lock.

One of the primary objects of my invention is to provide novel means for engaging a sliding drawer for holding the same in an adjusted position against accidental movement, thereby insuring the proper positioning of the drawer at all times.

Another important object of my invention is the provision of a friction lock for a sliding drawer, in which the drawer can be held either in an open or closed position against accidental movement or in an adjusted partially opened position against accidental movement.

A further prime object of my invention is the provision of novel means for forming the friction lock itself, whereby an inexpensive and durable structure will be had, which at the same time will give the maximum amount of usefulness.

With these and other objects in view, the invention consists in the novel construction, arrangement and formation of parts, as will be hereinafter more specifically described, claimed, and illustrated in the accompanying drawing, in which drawing:

Figure 1 is a front elevation of an article of furniture showing my improved drawer guide and lock incorporated therewith, parts of the view being shown broken away and in section.

Figure 2 is detail section taken on the line 2—2 of Figure 1 looking in the direction of the arrows.

Figure 3 is an enlarged detail sectional view illustrating my improved drawer guide and lock.

Figure 4 is a detail sectional view taken at right angles to Figure 3 and on the line 4—4 of Figure 3, looking in the direction of the arrows.

Figure 5 is a fragmentary detail perspective view of the drawer guide strip.

Figure 6 is a detail perspective view of the casting for receiving the friction ball lock, and

Figure 7 is a detail perspective view of a slightly modified form of casing for receiving the ball lock.

Referring to the drawing in detail, wherein similar reference characters designate corresponding parts throughout the several views, the letter A generally indicates an article of furniture which can be considered of any desired type. In the present instance I have shown my invention incorporated with an article of furniture which is of the type generally known as a household shoe polishing stand. As shown, the article of furniture A includes a body 10 having support-

ing legs 11, and with a drawer opening 12 in its front wall. A drawer 13 is slidable in the body 10 through the drawer opening 12, and suitable guides 14 are provided for the drawer.

All of the above described structure may be considered of conventional or ordinary construction, and my invention relates to a novel means for guiding the drawer during the opening and closing thereof and for frictionally locking the drawer in either a closed or opened position, and in any adjusted partially opened position.

In accordance with my invention I provide a bearing and guide strip 15, which can be made of metal or the like and this strip is secured to the lower edge of the drawer 13 directly above one of the drawer guides 14. The strip 15 preferably is made of metal and the lower edge of the drawer is rabbeted or grooved so that the strip can be countersunk within the lower wall of the drawer. At spaced points the bearing and guide strip 15 is provided with struck in pits 16, which form keeper members for a purpose which will be later described.

Operating in conjunction with the guide and bearing strip 15 I countersink within the drawer guides 14 a casing 17, which forms the housing for the friction lock and bearing member, as will now be described. The housing 17 is of a cylindrical shape and is preferably formed from sheet metal and the construction thereof forms one of the salient parts of my invention. The inner edge of the casing 17 has formed thereon a pair of diametrically disposed fingers 18 and 19. The finger 19 is bent inwardly to extend diametrically across the casing as clearly shown in Figure 6 and is of a substantially U-shape in longitudinal section and has its intermediate or bight portion indented as at 20 to form a seat for the bearing ball and friction lock member 21. The other finger 18 is now bent down and extends across the lower end of the casing and engages the end of the finger 19 at its point of connection with the casing. By this arrangement the finger 18 will serve to limit downward movement of the finger 19 and also serve to brace the casing and prevent it from being bent out of shape when it is driven into place.

The finger 19 forms a resilient leaf spring on which the ball bearing and friction lock seats and thus the finger normally urges this ball outward of the casing. The casing 17 is imbedded or countersunk within the drawer guide 14 adjacent to the front of the drawer 13, when the same is in its closed position, so that the ball 21

will be urged into engagement with the first keeper member 16. Thus this tends to frictionally hold the drawer in its locked position. When it is desired to open the drawer it is merely necessary to pull outward on the same until pressure is sufficient to unseat the ball 21 from the first keeper member, after which the ball acts upon the guide 15 in the nature of a bearing, and prevents the binding of the drawer on the bearing and guide strip 15. The innermost keeper member 16 forms a seat for the ball member when the drawer is pulled out to its fullest extent, and thus the same acts as means for frictionally locking the drawer in its extreme open position. The intermediate keeper members act as means for permitting the drawer to be held partially open in any preferred adjusted position.

The strength of the finger support 19 for the ball will of course vary with the thickness or temper of the metal used in making it and the casing, since it is of a continuous part of the casing. It can be designed to support any desired definite weight or pressure before springing, and at that event the giving or springing is necessary to prevent rigid binding or shock.

I lay particular stress on the formation of the casing 17, in that the same forms a cheap yet desirable structure.

In Figure 7 I have shown a slightly modified form of casing, which is generally indicated by the reference character 25. This casing 25 also includes a cylindrical side wall and a flat lower bottom wall 26, which has struck-out therefrom the resilient inwardly directed tongue 27. The tongue 27 is connected only at one end to the casing and is of the same character as the finger 19, and thus forms a seat and means for normally urging the ball bearing and lock toward the bearing strip or plate 15. The portions of the bottom at opposite sides of the tongue brace the casing and prevent it from being bent out of shape. Therefore, in both embodiments the casing will be prevented from becoming distorted and the ball will not become jammed in the casing.

Changes in details may be made without de-

parting from the spirit or the scope of this invention, but:—

What I claim as new is:

1. A device of the character described comprising a substantially tubular casing having a diametrically extending resilient finger projecting across its lower end, a freely rotatable ball yieldably supported in the casing by said finger and rotatable in all directions, and means to brace the lower end of said casing and prevent distortion thereof. 80

2. A device of the character described comprising a cylindrical casing, a diametrically extending resilient finger at the lower end of said casing extending across the casing and bent upwardly into the casing to form a seat, a ball resting upon said seat within the casing, and a second tongue extending across the lower end of said casing and serving to brace the casing and limit downward movement of the first tongue. 90

3. A device of the character described comprising a cylindrical casing, a resilient finger extending diametrically across the lower end of said casing and integrally connected to the casing at one end, said finger being bent to assume an inverted U-shape and extending into the casing and formed with a seat intermediate its inner ends, a ball in the upper portion of said casing resting in the seat of said finger and yieldably supported by the tongue, and a second finger extending across the inner end of said casing and connected to the casing at one end and contacting with the casing at the other end and serving to brace the casing and limit downward movement of the first finger. 100

4. As a new article of manufacture, a bearing comprising a substantially tubular casing having a diametrically extending resilient finger formed integrally with one side of said casing and projecting across the lower end of said casing, a freely rotatable ball yieldably supported in said casing by said finger and rotatable in all directions, and said finger being bent inwardly of said casing and wholly shielded within its length within said casing. 110
